UNITED STATES PATENT OFFICE.

HARRY DORNIN WETHLING, OF ORANGE, NEW JERSEY.

ELECTRIC PERMUTATION LOCK.

Application filed August 11, 1922. Serial No. 581,227.

To all whom it may concern:

Be it known that I, HARRY D. WETHLING, a citizen of the United States, and a resident of Orange, in the county of Essex and State 5 of New Jersey, have invented a new and Improved Electric Permutation Lock, of which the following is a full, clear, and exact description.

This invention relates to electric locks and 10 has particular reference to an electric permutation lock, the same being in the nature of an improvement upon a prior patent granted to me August 8, 1922, and bearing United States Patent No. 1,425,428.

15 The present invention contemplates an electric permutation lock which is particularly designed for use in connection with the ignition system of motor vehicles, although the same may be employed in connection 20 with any desired electric circuit controlling the same.

One of the outstanding objects of the present invention resides in the provision of a 25 means for effectively locking an electric circuit in opened condition without the necessity of using a key or other similar detachable manipulating element.

As a further object the invention contemplates in an electric permutation lock, 30 means for facilitating the changing of the combination without removing the interior elements or opening up the lock housing.

More specifically where the lock is employed in connection with ignition systems 35 the invention contemplates means for mounting and closing the lock housing to preclude the possibility of an unauthorized person opening the same in a limited space of time.

40 As a still further object the invention aims to provide an electric permutation lock which is extremely simple in its construction, inexpensive to manufacture and install, and which is thoroughly reliable and highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning 55 of the terms in which the claims are expressed.

In the drawings—

Figure 1 is a front elevation of the lock as applied to the dash or instrument board 60 of a motor vehicle.

Fig. 2 is a side view thereof with the dash or instrument board in cross section.

Fig. 3 is a rear view.

Fig. 4 is a vertical longitudinal sectional view through the lock taken approximately 65 on the line 4—4 of Fig. 5.

Fig. 5 is a transverse sectional view taken approximately on the line 5—5 of Fig. 2.

Referring to the drawings by characters 70 of reference, A designates the dash or instrument board of a motor vehicle, B the coil box which is disposed in rear thereof, and C the circuit wires which extend from the coil box to the spark plugs or other instrumentalities 75 operated by the circuit.

The lock which constitutes the invention comprises a cup-shaped housing 10, the open front end of which is inserted through and snugly fits within an opening 11 in the dash or instrument board A. A cover plate 12 of 80 larger diameter than the housing 10 is fitted over the open front end and said cover plate is provided with an annular inwardly projecting flange 13 which snugly fits within the open end of the housing 10. Locking screws 85 14 extend radially through the housing and are anchored in the flange 13 to retain the cover plate in place. The outer peripheral portion 15 which extends beyond the outer periphery of the housing 10 constitutes an 90 abutment flange which lies against the front face of the dash or instrument board A. The coil box B which is provided with an outturned flange D at its open end against which a coil box cover plate E is arranged, 95 is brought into flat contact with the rear wall 16 of the housing 10 and screws 17 are passed through the walls 16 and anchored in the bosses F of the coil box cover plate to attach the coil box and housing together. 100 Stud bolts G are passed through openings in the flanges D of the coil box and lock nuts H are threaded on the stud bolts and bear against the coil box cover plate E to clamp the same against the flange D. The inner end of the stud bolts G are impinged against the inner face of the dash or instrument board A for the purpose of effecting the drawing of the peripheral portion 15 into flat engagement with the front surface 110 of the dash or instrument board A. A large number of stud bolts G are employed for

this purpose to act as a deterrent against the opening of the housing and removal of the coil box to prevent tampering with the lock or circuit wires by an unauthorized person. Under this arrangement the locking screws 14 are disposed within the opening 11 in the dash or instrument board to render their removal impossible until the stud bolts have been withdrawn. A bed plate 18 5 of insulating material is arranged within the space defined by the annular flange 13 and said bed plate is provided with an annular series of bearing openings 19 which align with similar bearing openings 20 in the 10 housing cover plate 12. A shaft 21 is mounted in each aligned bearing opening 19 and 20 and said shaft is provided with a reduced extension 22 which protrudes inwardly beyond the inner face of the bed 15 plate 18. A substantially circular head 23 of a non-conducting material is attached to the inner end of each extension 22 for turning movement therewith in one direction by means of a ratchet 22^a and each of said 20 heads is provided with a peripheral bridge plate 24 of a material which is a conductor of electricity. A coiled spring 25 is interposed between a washer 26 bearing against the inner face of the bed plate and an abutment 27 on the extension 22 for the purpose of impinging and frictionally engaging the 25 annular bead on the shaft 21 against the outer face of the housing cover plate 12. A plurality of supporting posts 29 are anchored 30 in the bed plate 18 and project outwardly therefrom, said posts being interposed between the adjacent heads 23. A bowed resilient contact element 30 is secured to the outer end of each post with the opposite extremities in frictional engagement with the 35 periphery of the heads. One of the posts and contact elements 29 is omitted from between two of the adjacent heads and at this point a pair of resilient contact arms 31 40 respectively engage the peripheries of the adjacent heads 23. The contact arms 31 are connected to and mounted on posts 32 which project inwardly from the bed plate and are anchored thereto. A conduit or circuit wire 45 J is led into the housing 10 through the aligned apertures 33 and 34 in the walls 16 and coil box cover E. The circuit or conduit wire J is broken and the opposite terminals thereof extend through the posts 32 50 to electrically connect the same to the contact arms 31. Under this arrangement the circuit will be closed only when all of the peripheral bridge plates 24 are bridging the contact elements 30 and the arms 31 at the 55 terminals of the circuit wire or conductor J. If one or more of the heads 23 is turned to dispose the peripheral bridge plate 24 out of bridging relation to the contacts, it is obvious 60 that the circuit will be broken or opened. In order to provide means for 65

guiding the operator in the manipulation of the switch heads 23, pointer arms 35 are attached to the outer projecting ends of the shafts 21 which pointer arms cooperate with the indicating indicia 36 inscribed on the 70 outer face of the housing cover plate 12. The pointer arms 35 are rendered adjustable for the purpose of changing the combination by detachably associating the same with the outwardly projecting portions of 75 the shafts 21. As illustrated the outwardly projecting portions 37 of the shafts are of multi-faced formation while the pointer arms are provided with multifaced openings 37. Retaining screws 39 serve to normally 80 hold the pointer arms over the portions 37.

When it is desired to lock the circuit in opened condition, one or more of the pointer arms are manipulated to rotate the shafts 21 and switch heads 23 whereby to dispose the 85 peripheral bridge plates 24 out of bridging relation to the contact elements 30 or contact arms 31. To close the circuit the operator having knowledge of the particular combination manipulates the pointer arms 90 to the proper indicating character 36. A change in the combination may be readily effected without opening the housing by simply removing the retaining screws 39, withdrawing the pointer arms 35 from the portions 37 of the shaft and replacing the same 95 thereover in a different position.

It will thus be seen that an electric permutation lock has been provided which is extremely simple in its construction and 100 which is especially applicable for use in connection with the ignition system of motor vehicles whereby to preclude the possibility of operation of the motor by an unauthorized person.

I claim:

1. A permutation ignition lock including a housing into which one of the conductors of the ignition system extends, a plurality of switches arranged in series in said conductor and located in the housing, each of said switches comprising a rotary switch head having a peripheral bridge piece and a resilient contact interposed between the adjacent switch heads and respectively engaging the peripheries thereof, shafts extending through one of the walls of the housing having the switch heads connected therewith for turning movement in one direction, and complementary means at the outer end of each shaft and on the outer surface of the housing for indicating to the operator the closed and open condition of the switches.

2. A permutation ignition lock including 125 a housing into which one of the conductors of the ignition system extends, a plurality of switches arranged in series in said conductor and located in the housing, each of said switches comprising a rotary switch 130

head having a peripheral bridge piece and a resilient contact interposed between the adjacent switch heads and respectively engaging the peripheries thereof, shafts extending through one of the walls of the housing having the switch heads connected therewith for turning movement in one direction, and complementary means at the

outer end of each shaft and on the outer surface of the housing for indicating to the operator the closed and open condition of the switches, said complementary indicating means for each switch being relatively adjustable with respect to each other to vary the combination.

HARRY DORRIN WETHLING.
